RIGGING FOR SADDLES

Elliott O. Wilson, Denver, Colo., assignor to The
Denver Dry Goods Co., Denver, Colo.

Application May 25, 1935, Serial No. 23,382

5 Claims. (Cl. 54—46)

This invention relates to a rigging for riding saddles, and has for its principal object the provision of means for attaching the latigo and cinch to the saddle rigging which will avoid the usual lump or bunch at this point which causes rib sores on the mount and discomfort to the legs of the rider.

In the usual "all leather" saddle, the latigo and cinch is passed through an opening in the rigging leather itself. This causes an uncomfortable thickness in this point since it more than doubles the thickness at this point over the normal thickness of the rigging strap and creates an uncomfortable and harmful bulge.

15 The present invention is designed to eliminate this "bulge" at the point of attachment of the latigo or cinch.

Another object of the invention is to provide an attachment member which will be very secure, 20 able to withstand the strains to which the rigging is usually subjected, and yet which will be economical to manufacture.

Other objects and advantages reside in the detail construction of the invention, which is 25 designed for simplicity, economy, and efficiency. These will become more apparent from the following description.

In the following detailed description of the invention reference is had to the accompanying 30 drawing which forms a part thereof. Like numerals refer to like parts in all views of the drawing and throughout the description.

In the drawing:—

35 Fig. 1 illustrates a saddle tree with its rigging attached. In this view, the saddle leather, skirt, flaps, stirrup straps, etc., have been omitted.

Fig. 2 is a section through the rigging leather, taken on the line 2—2, Fig. 1.

40 Fig. 3 is a similar section, taken on the line 3—3, Fig. 1.

Fig. 4 is a detail face view of the attachment plate employed in this invention.

Fig. 5 is a perspective view of a modified form 45 of attachment plate.

In the drawing, a typical saddle tree has been 50 illustrated at 10, to each side of which the usual rigging leathers 11 are attached by means of rivets 12, or in any other suitable manner.

55 In carrying out the objects of this invention, the rigging leather 11 is two-ply, and is stitched together along its edges by means of suitable stitching 13. The invention contemplates forming a relatively deep upwardly extending notch 14 in the bottom edge of the rig-

ging leather 11, and placing a plate 15 across the open mouth of this notch.

The plate 15 is shown in detail in Fig. 4, and is formed with two obovate flaring ears. Two transverse bars 17 extend between the ears 16 to receive the loops of the latigo, or cinch, indicated at 18. The blade-like ears are perforated as indicated at 19.

In installing the plate 15, the two ears 16 are forced between the two plies of the rigging leather 10 11 and riveted in place therein by means of suitable rivets 20 which are passed through the two-ply and through the openings 19 of the plates.

At one side of the saddle, the cinch 18 will be permanently secured about the lower transverse bar 17; at the other side the latigo will be 15 looped over both bars 17.

It is desired to call attention to the fact that after the latigo has been wrapped around its 20 transverse bar 17, it does not project on either side beyond the face of the rigging leather 13 so that no objectionable bulge or bump is formed at this point.

In Fig. 4 the plate is shown with a slight offset 25 at 21 which projects the bars 17 still further away from the horse so as to insure that the latigo will not project beyond the face of the rigging strap on the inside.

In Fig. 5 a modified form of attachment plate 30 is illustrated. In this form the ears are thickened as they approach the middle or attachment portion as shown at 22. The cross bar portion is then indented below this thickened portion forming a shoulder at each side as indicated at 23.

The thickened portions cause the two plies of 35 the rigging leather to be widely separated at this point so as to provide a deep channel for the wrappings of the latigo which will absolutely prevent the latter from projecting inwardly or outwardly to form an objectional bump for the rider or horse.

The offset form of Fig. 4 and the inset form of Fig. 5 both space the bars 17 from the saddle skirt so as to allow easy insertion of the latigo in 40 saddling.

While a specific form of the improvement has been described and illustrated herein, it is desired 45 to be understood that the same may be varied, within the scope of the appended claims, without departing from the spirit of the invention.

Having thus described the invention, what is claimed and desired secured by Letters Patent is:—

1. In a saddle: a tree; a rigging leather affixed 55

to said tree and having a notch formed in its bottom edge; a transverse bar for receiving a latigo extending across said notch; ears formed on the extremities of said bar; and imbedded in said leather.

2. In a saddle: a tree; a rigging leather secured to and extending downwardly about each side of said tree; each of said leathers being provided with an upwardly extending notch in its bottom edge and each consisting of two leather plies; and a plate member extending across the opening of said notch at each side of said tree; ears formed on each of said plate members extending between the two plies of said rigging at each side of said notch; and means for securing said ears between said plies.

3. A latigo attachment member for saddle rigging leathers comprising: a pair of substantially parallel bars joined at their extremities and a flaring obovate extremity joined to each extremity of said pair of bars, said bars arranged to extend across and close the open side of a notch formed

in a rigging leather, said obovate extremities being formed to be imbedded in said leathers.

4. A saddle rigging leather comprising: two plies of leather arranged to be secured to a saddle tree at their extremities and provided with an inwardly extending open notch in their lower edges; a line of stitching securing the edges of said two plies and said notch together; a plate extending across the open side of said notch; ears formed on said plate, said ears being positioned between the two plies of said leather.

5. A saddle rigging leather comprising: two plies of leather arranged to be secured to a saddle tree at their extremities and provided with an inwardly extending open notch in the lower edges; a line of stitching securing the edges of said two plies and said notch together; a plate extending across the open side of said notch; ears formed on said plate, said ears being positioned between the two plies of said leather; and substantially parallel bar portions formed on said plate at the point where it crosses said notch.

ELLIOTT O. WILSON.
